UNITED STATES PATENT OFFICE

108,197

DESIGN FOR A DRESS

Marie Eileen Smith, New York, N. Y.

Application December 30, 1937, Serial No. 73,992

Term of patent 3½ years

To all whom it may concern:

Be it known that I, Marie Eileen Smith, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the tucks on the waist and skirt as shown, in combination with superimposed crochet flowers on the pockets and girdle, as shown.

I claim:

The ornamental design for a dress substantially as shown, and described.

MARIE EILEEN SMITH.
